THE NORRIS PETERS CO., WASHINGTON, D. C.

UNITED STATES PATENT OFFICE.

JOHN S. DUDLEY, OF MARION, OHIO.

BOOK-HOLDER.

No. 841,237.

Specification of Letters Patent.

Patented Jan. 15, 1907.

Application filed January 29, 1906. Serial No. 298,526.

To all whom it may concern:

Be it known that I, JOHN S. DUDLEY, a citizen of the United States, residing at Marion, in the county of Marion and State of Ohio, have invented certain new and useful Improvements in Book-Holders, of which the following is a specification.

My invention relates to devices for holding books in a substantially upright position for reading, but preferably for copying therefrom, and is especially adapted to be used in connection with large books—such as ledgers, dockets, registers, &c.—and has for one of its objects the provision of a holder by which the book may be adjusted at any angle within certain limitations.

Another object is the provision of an adjustable marker for indicating the lines on the book, the vertical rod carrying the marker being so constructed that it may be secured to prevent lateral displacement when the book is not opened evenly.

Another object of the invention is the provision of removable and replaceable blocks on the book-edge supporter to support the edges of the leaves, so that they will lie perfectly flat, said blocks being made of different thicknesses, so as to provide for the different book-binder's gages.

The details of construction of my invention will be described hereinafter, and illustrated in the accompanying drawings, in which—

Figure 1 is a front view in elevation of my improved book-holder; Fig. 2, a side view; Fig. 3, a detail view of the means to adjust the support-brace; Fig. 4, a longitudinal sectional view of the middle fragment of the shelf; Fig. 5, a top plan view of said middle fragment, and Fig. 6 a bottom view of one of the leaf-edge-support blocks.

In the drawings similar reference characters indicate corresponding parts throughout the several views.

A A represent two boards of any desired size secured together by means of cross-bars B B, the edges of the boards A A being spaced at a distance from one another and the cross-bars B B therebetween curved, as shown at b, to receive the back of the book, the boards A A being adapted to support the covers thereof.

C represents a shelf secured adjacent to the lower edges of boards A A to hold the lower edges of the covers of the book and having dovetail-sockets c in each end to receive a dovetail-tenon d on the under side of block D,

the purpose of said blocks being to support the lower edges of the leaves of the book when in place and insuring that the leaves will lie perfectly flat. The construction of the 60 socket c and tenon d admits of the removal and displacement of the blocks D, as desired, it being understood that blocks of varying thicknesses may be provided to provide for the varying gages used by book-binders between the edges of the leaves and the edges of the covers.

E represents legs secured to the lower portion of each board A, having secured thereto a non-abrasive knob or ferrule e.

F represents an angular lug secured to the back of each board A, each having a hole f, in which is pivotally secured an angular projection g on U-shaped brace G, which supports the boards A A, H being lengths of rubber 75 tubing or other non-abrasive material on the cross-arm G' of brace G.

I represents a socket cut into shelf C transversely thereof and J a piece of slotted sheet metal secured thereover and having its end 80 turned down on the edge of shelf C, as shown at j, and formed with a hook K, on which is adapted to be secured one of the links of chain L, having one end secured to the cross-arm G'. This construction admits of adjusting the angle of the boards A A and the hook thereon, as desired, by the reader or copyist, the book K being caught in the link of chain L necessary for proper adjustment.

M represents a rod secured to the curved 90 portion b of the cross-bars B B and having secured to its upper end a spring-arm N, on which is slidably mounted a line-marker O, which is held in various positions on said rod N by frictional contact therewith or 95 may be secured thereto by means of setscrew P.

In order to prevent side play of the spring-arm N, caused by the book on the holder being opened near its front or back, and the consequent uneven pressure exerted on line-marker O, I provide a cross-piece or button n on the lower end of said spring-rod N, adapted to fit into socket I, said cross-piece or button n holding the rod N in the center of the 105 book, notwithstanding the unevenness of pressure as above stated.

Having thus described my invention, what I claim is—

1. In combination with a book-holder consisting of upright boards and a shelf thereon, a block removably and replaceably secured

to the shelf at each end thereof and spaced apart from the upright boards so as to leave room for the edge of a book-cover between said boards and block to seat on the shelf, 5 while the edges of the leaves rest on top of the blocks, substantially as shown and described.

2. In combination with a book-holder consisting of upright boards and a shelf secured thereto having dovetail sockets in its ends, blocks having dovetail tenons to fit said sockets, said blocks being formed so that when in position they are spaced apart from the upright boards leaving a space between said 15 boards and blocks for the edges of a book-cover to seat on the shelf while the edges of the leaves rest on the blocks, substantially as shown and described.

3. In a book-holder, in combination with upright boards, and cross-bars connecting said boards, a spring-arm secured to said cross-bars, and a line-marker slidably mounted on said spring-arm, substantially as shown and described.

25 4. In a book-holder, in combination with upright boards, and cross-bars connecting said boards, a spring-arm secured at one end to said bars, a line-marker slidably mounted on said spring-arm, and means to hold said 30 spring-arm from lateral displacement, substantially as shown and described..

5. In a book-holder, in combination with

upright boards, cross-bars connecting said boards, and a shelf secured to the boards having a socket in the middle thereof, a spring-arm secured at one end to said cross-bars, and a cross-piece on the free end of said spring-arm and adapted to fit into said socket in the shelf, substantially as shown and described. 35

6. In a book-holder, in combination with upright boards, a shelf secured to said boards having dovetail sockets in its ends and a socket in its middle, a slotted piece of metal secured over said middle socket and having its end bent to form a hook, blocks having 45 dovetail tenons to fit the sockets in the ends of the shelf, cross-bars connecting said upright boards having curved portions therebetween, a rod secured to said curved portions, a spring-arm having one end secured to said 50 rod, a cross-piece at the other end of the arm to fit into the socket in the middle of the shelf, a line-marker slidably mounted on said spring-arm, a U-shaped brace pivotally secured to said boards, and a chain secured to 55 said brace, the links of said chain being adapted to be secured to the hook aforesaid, substantially as shown and described.

In testimony whereof I hereto affix my signature in the presence of two witnesses.

JOHN S. DUDLEY.
